CLAIM

The ornamental design for a second layer drip edge, as shown and described.

DESCRIPTION

FIG. 1 is a rear, bottom, left-side perspective view of a second layer drip edge, showing our new design;

FIG. 2 is a front, bottom, left-side perspective view thereof;

FIG. 3 is a bottom elevation view thereof;

FIG. 4 is a top elevation view thereof;

FIG. 5 is a right-side elevation view thereof;

FIG. 6 is a left-side elevation view thereof;

FIG. 7 is a rear elevation view thereof; and,

FIG. 8 is a front elevation view thereof.
